LADY'S SHOE

Filed Sept. 26, 1938

UNITED STATES PATENT OFFICE

2,210,841

LADY'S SHOE

James C. Pape, Larchmont, N. Y., assignor to
I. Miller & Sons, Inc., Long Island City, N. Y., a
corporation of New York

Application September 26, 1938, Serial No. 231,714

5 Claims. (Cl. 36—45)

This invention relates to shoes, more particularly to shoes of the pump type.

It is well known that low shoes such as pumps frequently cause great discomfort and pain to the wearer due to the fact that the front edge of the upper at the foot opening binds tightly against or cuts into the wearer's instep. This serious objection arises from the necessity that the securing of the pump on the wearer's foot be obtained by reason of a relatively tight fit of the pump at the instep of the wearer's foot. For this reason it is well understood by shoe manufacturers that the points at the top edge of the upper at the heel and at front edge of the foot opening centrally of the latter are critical points and must be accurately determined in order to produce a pump which will properly fit the wearer's foot, not only when the pump is new but for a reasonable period of time of wear. It is important therefore to prevent excess elongation of the longitudinal median line of the foot opening, that is the distance between the rear and front points at the top edge of the upper, in order to prevent bulging of the sides of the upper and in order generally to preserve the proper fit, shape and appearance of the pump on the wearer's foot.

One object of the invention, therefore, is to provide a pump constructed and arranged to obviate the above mentioned serious objection in respect to the discomfort due to the tight binding against or cutting of the wearer's instep, and which is nevertheless so made that the proper fit thereof on the wearer's foot is preserved, whereby to prevent bulging of the sides of the upper at the pump and other distortions of the upper which result in impairing the shape, appearance and proper fitting of the pump.

Another object of the invention is to provide a pump which has an inextensible binding tape at the top edge of the upper whereby to prevent stretching or undue elongation of the distance between the above mentioned critical points at the rear and front edges of the upper, and to accomplish this while at the same time constructing the upper at the front edge of the foot opening in such manner as to substantially eliminate the cutting action of the front edge of the upper of the pump on the wearer's instep.

A yet further object of the invention is generally to provide a pump of improved construction in respect to the comfort and continued proper fit and appearance thereof during wear.

The above objects of the invention and other objects which might hereinafter appear will be more fully understood from the following description considered with reference to the accompanying drawing.

In the drawing:

Fig. 1 is a perspective view of a pump embodying the present invention;

Fig. 2 is a plan view, on a larger scale, of the front portion of the pump shown in Fig. 1;

Fig. 3 is a fragmentary view on a larger scale of the inner front portion of the upper of the pump adjacent the front of the foot opening;

Fig. 4 is a sectional view on the line 4—4 of Fig. 1.

Referring now to the drawing in detail, the low shoe 10, here shown as a lady's pump, comprises as usual an upper 12, a sole 14 and a relatively high heel 15. In accordance with the present invention, the upper 12 is provided at the front edge of the foot opening with a yieldable portion 16 composed in part at least of elastic leather which is now readily available on the market. Said elastic leather is as smooth as ordinary inelastic leather and has the same appearance as the latter. Thus when the upper 12 has its outer layer 12a composed, for example, of suede, which is extensively used in the uppers of pumps and similar low shoes, the exposed layer of yieldable portion 16 may likewise be composed of suede leather which, however, is elastic although the rest of the front of the pump in the exposed layer thereof may be and is preferably inelastic.

Yieldable portion 16 comprises an outer or exposed layer of leather 18 and an inner layer 20 of elastic sheet material, for example "Lastex", said layers 18 and 20 being adhesively united throughout their contiguous surfaces, usually by rubber cement, said layers being stretchable and contractable without producing wrinkles in layer 18. The upper edge portion of leather layer 18 is folded inwardly to provide an inturned margin 24 and a smooth folded edge 22 at the front edge of the foot opening for engagement with the wearer's foot. Said inwardly folded marginal portion 24 is relatively narrow so as not to interfere substantially with the elasticity of the composite material constituted by layers 18 and 20, and a strip of elastic tape 26, the ends of which are indicated at 27, is secured at its opposite side edges to layers 18 and 20 by lines of zig-zag stitching 28 and 30. The front portion 32 of the lining of the upper extends rearwardly beyond the forward edge 19 of leather layer 18 and overlaps tape 26 and is secured to yieldable portion 16 by a line of stitching 34. The lines of stitching 28 and 34 pass through the layers of material to the outer surface of the shoe, as shown in Figs. 2 and 4. Yieldable portion 16 can stretch and contract in a direction longitudinally of the front edge of the foot opening, that is, in a direction across the shoe from one side to the other. It will be understood that the edge 36 of the lining 32 terminates a substantial distance forwardly of the folded edge 22 of yieldable por-

tion 16 so as not to interfere with the elasticity and yieldability of said portion 16.

The top edge of upper 12 is provided with an inextensible binding tape 38 which extends completely around the shoe and has a front portion 38a spaced forwardly of the front edge of the foot opening defined by folded edge 22 of yieldable portion 16. Said inextensible tape 38 may be composed of any of the well known materials used as binding tapes at the edges of low shoes such as pumps, a grosgrain binding tape, for example, being suitable for the purpose of the present invention. It will be understood that said inextensible binding tape 38 prevents the top edge portion of the upper opening from stretching and thereby prevents elongation of said edge portion of the upper and obviates bulging of the side of the upper and other distortions thereof which impair the appearance, shape and fit of the pump on the wearer's foot. On the other hand, yieldable portion 16 which is in engagement with the part of the wearer's instep, prevents the front edge of the upper from cutting into the wearer's instep. It will be observed that the opposite end portions 40 of yieldable portions 16 terminate substantially at the ends of the front edge of the upper at the foot opening, while the inextensible tape 38 continues forwardly of said end portions 40 and extends around the front edge of the foot opening forwardly of the exposed edge 22 of said yieldable portion. In order to obtain best results, it is preferred to locate edge 22 of the foot opening one-eighth of an inch rearwardly of where the front edge of the foot opening would be if the pump were of conventional construction, while the front end of the shoe opening edge of that part of the upper 12 that is provided with inextensible tape 38a is located one-eighth of an inch forwardly of where the front edge of the upper at the foot opening would be if the pump were of conventional construction. Thus the edge 22 is located rearwardly of the normal throat line and the inextensible tape portion 38a is located forwardly of the normal throat line as compared with a pump of conventional construction. This has been found to provide an upper which engages the wearer's foot to hold the same securely thereon, and yet prevents pain or discomfort to the wearer due to the above mentioned cutting action which usually arises in wearing pumps of conventional construction, that is pumps which have relatively unyieldable edge portions at the front of the foot opening.

Thus it is seen that the pump constructed as herein shown and described is well adapted to accomplish the objects of the present invention. It will be understood, however, that the invention may be embodied otherwise than as here shown and that in the preferred embodiment herein illustrated certain changes in details of construction and arrangement of parts may be made. Therefore I do not wish to be limited precisely to the form of the invention herein shown or described, except as may be required by the scope of the appended claims.

Having thus described my invention, what I claim and desire to secure by Letters Patent is:

1. A low shoe such as a pump comprising an upper having an inextensible binding tape extending completely around the shoe at the foot opening, the front portion of said tape being spaced forwardly of the front edge of the upper at the foot opening, and forwardly of the normal throat

line, and the upper having a yieldable and elastic portion at said front edge of the foot opening extending rearwardly of said front portion of the inextensible tape and beyond the normal throat line and terminating in an edge defining the front edge of said foot opening. 5

2. A low shoe such as a pump comprising an upper having an inextensible binding tape extending completely around the shoe at the foot opening, the front portion of said tape being spaced forwardly of the front edge of the upper at the foot opening and forwardly of the normal throat line, and the upper having a yieldable portion of elastic leather at said front edge of the foot opening extending rearwardly of said front portion of the inextensible tape and beyond the normal throat line and terminating in an edge defining the front edge of said foot opening. 10

3. A low shoe such as a pump comprising an upper having an inextensible binding tape extending completely around the shoe at the foot opening, the front portion of said tape being spaced forwardly of the front edge of the upper at the foot opening, and the upper having a yieldable elastic portion at said edge of the foot opening extending rearwardly of said front portion of the inextensible tape, said yieldable portion of the upper comprising an exposed continuous layer of leather and an inner layer of elastic sheet material adhesively united together in stretchable and contractable relation and terminating in an edge defining the front edge of said foot opening. 20

4. A low shoe such as a pump comprising an upper having an inextensible binding tape extending completely around the shoe at the foot opening, the front portion of said tape being spaced forwardly of the front edge of the upper at the foot opening, and the upper having a yieldable elastic portion at said front edge of the foot opening extending rearwardly of said front portion of the inextensible tape, said yieldable portion of the upper comprising an exposed continuous layer of leather and an inner layer of elastic sheet material adhesively united together in stretchable and contractable relation, said exposed layer of said yieldable portion terminating in a narrow inwardly folded marginal portion defining the front of said foot opening, said marginal portion being yieldable and elastic. 30

5. A low shoe such as a pump comprising an upper having an inextensible binding tape extending completely around the shoe at the front opening, the front portion of said tape being spaced forwardly of the front edge of the upper at the foot opening, and the upper having a yieldable elastic portion at said front edge of the foot opening extending rearwardly of said front portion of the inextensible tape, said yieldable portion of the upper comprising an exposed continuous layer of leather and an inner layer of elastic sheet material adhesively united together in stretchable and contractable relation, said yieldable portion having a narrow inwardly folded marginal portion at the front edge of the foot opening, and an elastic tape secured to said folded marginal portion on the inside of the shoe forwardly of the folded edge at the front of the foot opening and overlapping the inner edge of said folded portion, said folded front edge portion defining the front edge of the foot opening. 40
